US0D1041079S

(12) United States Design Patent (10) Patent No.: US D1,041,079 S
(45) Date of Patent:  Sep. 3, 2024

(54) EYELASH TWEEZERS

(71) Applicant: QINGDAO JIAHE YONGRUN BEAUTY TECHNOLOGY CO., LTD., Shandong (CN)

(72) Inventor: Chao Yu, Shandong (CN)

(73) Assignee: QINGDAO JIAHE YONGRUN BEAUTY TECHNOLOGY CO., LTD., Shandong (CN)

() Term: 15 Years

(21) Appl. No.: 29/842,782

(22) Filed: Jun. 15, 2022

(51) LOC (14) Cl. 28-03

(52) U.S. Cl. ..... USPC D28/55

(58) Field of Classification Search
